UNITED STATES PATENT OFFICE.

WILLIAM W. JACKSON, OF PHILADELPHIA, PENNSYLVANIA, ASSIGNOR TO
MACKELLAR, SMITHS & JORDAN, OF SAME PLACE.

DESIGN FOR A FONT OF PRINTING-TYPES.

SPECIFICATION forming part of Design No. 11,659, dated February 24, 1880.

Application filed January 20, 1880. Term of patent 14 years.

To all whom it may concern:

Be it known that I, WILLIAM W. JACKSON, (assignor to MACKELLAR, SMITHS & JORDAN,) of the city and county of Philadelphia, Pennsylvania, have invented and produced a new and original Design for a Font of Printing-Types, of which the following is a specification.

The nature of my design is clearly shown in the accompanying typographic impression, to which reference is made.

It consists of shaded ornamental capital letters and figures.

The up-and-down portions of the letters consist of a heavy line upon the right, shaded by a lighter line, and a light line upon the left. The face of the letters is shaded by a series of light inclined lines.

The up-and-down portions of the letters B, D, E, F, H, I, K, L, P, R, and U are concaved upon the left, so that the upper and lower terminations are broader than the rest of the up-and-down portions.

The letter A is provided upon the left with a heavy triangular termination, from which proceeds a light line, and its right-hand termination at the top is inclined, as shown.

In the letters F, H, I, K, M, P, R, T, and Y the top and bottom terminations are broader than the rest of the up-and-down portions.

The letters C, F, and G have angular terminations upon the upper right hand, as shown, and in the E, S, and Z both terminations are angular, and in the letter L the lower termination, and in the letter T both the upper 35 terminations, are so designed.

In the letters M, N, V, and W the inclined portions of the letters have the concaved terminations, as shown, upon the right at the base of each letter.

The face of the letters near the lower portions is further ornamented by the heavy triangular figures, as shown.

In the numerals the character of the design is preserved, the upper portions of the 1 and 4 being concaved upon the right, as shown, and in these figures also the lower portions are wider than the rest of the up-and-down portions.

Having now set forth my invention, what I claim as new is—

The design for a font of printing-types, as shown and described.

WM. W. JACKSON.

In presence of—

GEO. WM. WITHAM,
H. METIUS.
